DESIGN FOR A RECIPE BOX

Louis A. Pelton, Baltimore, Md.

Application August 24, 1934, Serial No. 53,037

Term of patent 3½ years

To all whom it may concern:

Be it known that I, Louis A. Pelton, a citizen of the United States, residing at Baltimore city and State of Maryland, have invented a new, original, and ornamental Design for Recipe Boxes, of which the following is a specification, reference being had to the accompanying drawing, forming part thereof.

In the drawing there is shown in

I claim:

The ornamental design for a recipe box as shown.

LOUIS A. PELTON.
